RAY C. NEWHOUSE, OF WAUWATOSA, WISCONSIN, ASSIGNOR TO ALLIS-CHALMERS
MANUFACTURING COMPANY, OF MILWAUKEE, WISCONSIN, A CORPORATION OF
DELAWARE

COMMINUTING BODY

Application filed May 26, 1930. Serial No. 455,594.

This invention relates to improvements in the construction of comminuting or grinding mills for rock, ore and similar materials and particularly to an improved form of comminuting body adapted for use in such mills.

An object of the invention is to provide a grinding body of such form that it will tend to engage similarly formed adjacent grinding bodies in the mill along surfaces instead of lines and points, thereby enhancing the comminuting effect upon the material. Another object is to provide a grinding body having tooth-like projecting portions which make rolling contact with the projecting portions of similarly formed adjacent bodies which coaction permits more of the power supplied to the grinding mill to be expended in reducing the oversize material rather than to still further reduce the material already sufficiently fine, thereby increasing the efficiency of the grinding mill.

It has been customary in the prior art to employ several types of grinding bodies in comminuting mills of the tube and ball types. With the use of the ordinary flint pebbles and of iron spheres or balls, it has been found that there is ordinarily only point coaction between the adjacent bodies, thus eliminating the desirable comminuting effect which results from surface coaction. One of the types of grinding bodies of the prior art which appears to provide a desirable surface coaction is essentially spherical in form but having opposite spherical cavities. This type of grinding body by reason of its conformation is, however, limited to be formed by casting or with the use of dies. To construct the bodies by casting requires the expenditure of considerable time while to construct them with the use of dies requires heavy and therefore costly forging machinery. The grinding bodies of the present invention can be formed by merely cutting off desired lengths from a hot drawn or rolled bar of steel having the desired characteristics and of a substantially spur gear shaped cross-section.

A clear conception of an embodiment of the invention may be had by referring to the

drawings accompanying and forming a part of this specification in which like reference characters designate the same or similar parts in the various views.

Fig. 1 is a diagrammatic disclosure of a tube mill having the invention applied therein.

Fig. 2 is a fragmentary sectional view of a portion of the mill and shows a plurality of comminuting bodies in grinding relation with a material to be ground thereby.

Fig. 3 is an end view of the preferred form of comminuting or grinding body.

Fig. 4 is a front view of the body shown in Fig. 3.

Fig. 5 is an end view of a modified form of comminuting or grinding body.

Fig. 6 is a front view of the body shown in Fig. 5.

Referring to Figs. 3 and 4 it will be seen that each of the comminuting or grinding bodies 1, is generally cylindrical and substantially of a round tooth spur gear shaped cross-section. In order to effect a maximum surface coaction between the bodies, the ribs or tips 2 of each of the bodies 1 are arc shaped, as shown at 3, as are also the furrows or tooth-root defining portions 4. The radii of these two arc surfaces are preferably made equal and their centers to lie in the same circle of a mean diameter so as to obtain the maximum rolling effect, surface coaction and uniform wearing qualities. Although the length of the body may be different for various mills and materials, a length which is about twice that of the diameter of the mean diameter circle is the preferred length of the bodies.

When the grinding bodies 1 are placed within a mill grinding chamber, they assume various positions as indicated in Fig. 2, the ribs or tips of the teeth 2 of some of the bodies having surface coaction with the furrows or tooth-root defining portions 4 of adjacent bodies. As the mill is rotated, the adjacent bodies roll or slide relatively to each other at the coacting surfaces and tend to reduce the material 5 between the relatively moving bodies to a fine powder. The specific spur gear shape of the body provides not only an increased effective grinding surface in

the intermeshed relation of the bodies but also permits of the body which has been raised and allowed to fall by gravitation to impart a rotary motion to those adjoining and thus increase their rolling activities.

Further the extensive surface coaction present in this form of comminuting body effects a very appreciable increase in the efficiency of the mill in which the body is used. Less power supplied to the mill will be expended in reducing those portions of the material already sufficiently fine and consequently more of the power supplied to the mill will be expended in reducing those portions of the material that are oversized.

It will further be noted that the uniform cross-section of the bodies permits their being constructed from hot drawn or rolled steel bars of considerable length by merely cutting the bar in the desired lengths and thus effect a great saving in cost of manufacture over what was required to form the bodies of the prior art which were either formed by casting or with the use of dies.

While the bodies of Figs. 3 and 4 have been disclosed as having six ribs or teeth, it will be apparent that they may have a lesser number as for instance three as shown in Figs. 5 and 6. This form of body 1' because of the lesser material intermediate the ribs or teeth is not as serviceable as the preferred form of body shown in Figs. 3 and 4.

It should be understood that it is not desired to limit the invention to the exact details of construction shown and described, for obvious modifications will occur to a person skilled in the art.

It is claimed and desired to secure by Letters Patent:

- 40 1. As an article of manufacture, a universally tumbling comminuting body wherein parallel transverse cross-sections are substantially alike and are bounded by curved lines which comprise joined alternately inwardly and outwardly disposed semi-circles of substantially equal radii and having their centers in the same circle.
- 45 2. As an article of manufacture, a universally tumbling comminuting body cylindrical in form and having longitudinal convex semi-circular ribs and longitudinal, concave semi-circular furrows, the centers of which are on the same mean diameter circle and whose radii are substantially equal and the length of said body being substantially twice the diameter of said circle.

In testimony whereof, the signature of the inventor is affixed hereto.

RAY C. NEWHOUSE.
